UNITED STATES PATENT OFFICE.

AMBROSE BARKLEY, OF PIPESTONE, MINNESOTA.

WEEDER.

No. 914,227.

Specification of Letters Patent.

Patented March 2, 1909.

Application filed February 21, 1908. Serial No. 417,080.

To all whom it may concern:

Be it known that I, AMBROSE BARKLEY, a citizen of the United States, residing at Pipestone, in the county of Pipestone and State of Minnesota, have invented a new and useful Weeder, of which the following is a specification.

The invention relates to improvements in weeders.

10 The object of the present invention is to simplify and improve the construction of weeders, and to lighten the draft and enable a relatively large weeder, operating on five rows of plants, to be easily handled by a team.

15 With these and other objects in view, the invention consists in the construction and novel combination of parts hereinafter fully described, illustrated in the accompanying drawings, and pointed out in the claims hereinafter appended; it being understood that various changes in the form, proportion, size and minor details of construction, within the scope of the claims, may be resorted to without departing from the spirit or sacrificing 20 any of the advantages of the invention.

In the drawings:—Figure 1 is a perspective view of a weeder, constructed in accordance with this invention. Fig. 2 is a longitudinal sectional view of the same. Fig. 3 is a 25 reverse plan view of the weeder.

Like numerals of reference designate corresponding parts in all the figures of the drawing.

The frame of the weeder is composed of a 30 pair of forwardly converging bars 1, connected at their rear portions by transverse bars 2 and 3 and secured at their rear ends to the top of an arched axle 4. The arched portion of the axle is composed of vertical sides and a 35 horizontal connecting top, the lower terminals of the sides being bent outwardly to form spindles 5 for the reception of ordinary carrying wheels 5^a. The weeder is strengthened by inclined braces 1^a, secured at their 40 lower ends to the sides of the arched portion of the axle and extending upwardly and forwardly therefrom to the lower faces of the bars 1. The upper or front ends of the inclined braces 1^a are secured to the bars 1 at 45 points beneath the transverse connecting bar 2. The front ends of the beams are connected together and fitted within a tapering metallic pole tip 6, to which a neck yoke 7 is centrally pivoted.

50 Mounted on the cross bar 2 are upwardly extending metallic arms 8, spaced apart to

receive a lifting lever 9 and having their lower ends 10 bent outwardly and secured to the upper face of the cross bar 2. The lifting lever, which is pivoted at an intermediate point by a pin or rivet 11, is connected at its front end by a pin or rivet 12 to a pair of upwardly extending metallic arms 13, which have their lower ends bent outwardly, and are secured to a transverse bar or member 14. 60 The transverse bar or member 14, which is preferably constructed of flanged metal, consists of a front vertical flange or wing and a rearwardly extending horizontal flange or wing, to which weeding teeth 15, 16 and 16^a 65 are secured. The teeth 15, 16 and 16^a, which are preferably constructed of spring metal, have downwardly curved rear portions, and are provided with upper approximately horizontal shank portions, which are 70 suitably secured to the horizontal flange of the transverse bar or member. The teeth 15, 16 and 16^a are arranged in sets of three, as clearly illustrated in Fig. 1 of the drawings, and the members of each set are of different lengths, the shank portions increasing in length from left to right, so that the teeth engage the ground different distances in rear of the transverse bar or member 14. The shortest tooth of one set is located next to 75 the longest tooth of the adjacent set, whereby sufficient space is afforded to permit accumulations to pass between the teeth of the weeder.

The transverse bar or member is connected with the frame of the harrow by a connection, consisting of a substantially V-shaped rear member 17 and a front member, composed of a pair of rods 18, secured at their front ends to the lower face of the 90 beams 1 and connected at their rear ends, the rear portions of the rods being bent downwardly and forwardly to form an eye 19, into which the front end of the V-shaped member is linked. The eye and the front 95 end of the V-shaped member form a hinge connection, and permit the transverse tooth carrying bar to be raised and lowered by the lifting lever 9. The hinge joint between the front and rear members also permits the 100 front tooth carrying bar or member to have a limited movement laterally of the agricultural implement. The front terminals of the rods 18 extend into the metallic tip 6, and the rear ends of the sides of the V-shaped member 17 are secured to the lower face of the 105 transverse tooth carrying bar 14.

The tooth carrying bar is held in an elevated position above the ground by means of a hook 20, pivoted at its lower end to the transverse bar 3, and provided at its upper end with a bill for engaging the lever. The weeder is also equipped with a ratchet bar 20^a, extending upwardly from the transverse connecting bar 3 and pivoted at its lower end to the same by the bolt, which pivots the hook 20 to the said bar 3. The ratchet bar 20^a is provided with a plurality of teeth, adapted to be engaged by the lever 9, whereby the teeth are adjustably supported in the ground. The teeth are adapted to draw themselves into the ground as far as the ratchet bar will permit. The lifting lever 9 is provided at its rear with a handle portion or grip, and the machine is equipped with a seat 21, located in rear of the lifting lever and having substantially V-shaped supporting arms or standards 22, secured to the rear portions of the beams at the inner sides thereof.

The draft animals are connected directly to the tooth carrying bar or member by means of a bracket 23, consisting of a curved bar, secured at its ends to the vertical flange of the transverse bar or member 14 and extending forwardly at the center thereof and supporting a doubletree 24. The doubletree, which is equipped with the usual swingtrees 25, is centrally pivoted to the bracket 23 by a bolt 26, or other suitable fastening means. This direct connection of the team with the tooth carrying bar or member operates to lighten the draft, and enables a team to readily handle a weeder of sufficient size to cover five rows of plants. The weeder is also adapted for cultivating grain when the plants are from three to five inches high.

Having thus fully described my invention, what I claim as new and desire to secure by Letters Patent, is:—

1. An agricultural implement comprising a frame including forwardly converging beams connected at their front ends, an axle supporting the rear ends of the beams, a neck yoke connected to the front ends of the beams, a transverse tooth-carrying bar located beneath the rear portion of the said frame, a connection extending from the transverse bar to the front portion of said frame, and whiffletrees connected with the transverse bar.

2. An agricultural implement comprising a frame including forwardly converging beams connected at their front ends, an axle supporting the rear ends of the beams, a neck yoke connected to the front ends of the beams, a transverse tooth-carrying bar located beneath the rear portion of the said frame, a connection extending from the transverse bar to the front portion of the said frame, a central bracket mounted on the transverse bar and extending forwardly

therefrom, a doubletree centrally connected with the bracket, and swingtrees located at opposite sides of the frame and connected with the ends of the double tree.

3. An agricultural implement comprising an axle, a frame including beams secured to and extending forwardly from the axle and connected together at their front ends, a transverse tooth-carrying bar located beneath the frame, and a connection consisting of front and rear members hinged together, the front member being connected to the front ends of the beams, and the rear member being secured to the tooth-carrying bar.

4. An agricultural implement comprising an axle, a frame including beams secured to and extending forwardly from the axle and connected together at their front ends, a transverse tooth-carrying bar located beneath the frame, and a connection composed of a rear substantially V-shaped member secured to and extending forwardly from the tooth-carrying bar, and a front member connected with the beams and provided with an eye receiving the V-shaped member and forming a hinge connection to permit the tooth-carrying bar to move upward and downward and also laterally of the frame.

5. An agricultural implement comprising an arched axle, beams connected at their rear portions to the axle and converging forwardly therefrom and secured together at their front ends, transverse bars connecting the beams at the rear portions thereof, a transversely disposed tooth-carrying bar located below the beams, a connection extending from the tooth-carrying bar to the front portions of the beams, a lifting lever fulcrumed on one of the transverse connecting bars and connected with the tooth-carrying bar, and a device mounted on the other transverse connecting bar for engaging the lever to hold the tooth-carrying bar in an elevated position.

6. An agricultural implement comprising an arched axle, beams connected at their rear portions to the axle, and converging forwardly therefrom and secured together at their front ends, transverse bars connecting the beams at the rear portions thereof, a transversely disposed tooth-carrying bar located beneath the beams, a connection extending from the tooth-carrying bar to the front portions of the beams, a lifting lever fulcrumed on one of the transverse connecting bars and connected with the tooth-carrying bar, a device mounted on the other transverse connecting bar for engaging the lever to hold the tooth-carrying bar in an elevated position, and a seat located in rear of the axle and having forwardly extending standards connected with the rear portions of the beams.

7. An agricultural implement comprising an axle, a frame connected with the axle, a

transversely disposed bar located below the frame and provided with spring teeth, a draft appliance connected with the tooth-carrying bar and located in rear of the front 5 end of the frame, a lever fulcrumed on the frame and connected with the tooth-carrying bar, a ratchet bar extending upward from the frame and arranged to engage the lever to support the teeth in the ground at 10 different elevation, and a connection located beneath the frame and extending longitudinally of the same from the front of the transverse bar to the front portion of the frame and connected with the said bar at opposite 15 sides of the point of connection of the transverse bar with the lever.

8. An agricultural implement comprising a frame, supporting wheels therefor, a bar located beneath the frame and extending 20 across the agricultural implement at a point in advance of the wheels and provided with teeth, a draft appliance connected with the tooth carrying bar and located at a point in rear of the front end of the frame, and a connection 25 independent of the draft appliance and located beneath the frame and extending from the front of the tooth carrying bar to the front portion of the frame, said connection permitting both an upward and downward 30 and a lateral movement of the tooth carrying bar.

9. An agricultural implement comprising a frame, wheels supporting the frame, a bar located below the frame and extending 35 across the agricultural implement at a point in advance of the wheels and provided with teeth, a connection located beneath the frame and extending longitudinally of the same from the front of the tooth carrying bar 40 to the front portion of the frame, and a draft appliance attached directly to the tooth carrying bar and located at a point in rear of the

front end of the frame and having whiffle-trees located at a point between the ends of the said connection.

45

10. An agricultural implement comprising a frame, wheels supporting the frame, a transverse bar located below the frame and extending across the agricultural implement in advance of the wheels and provided with 50 teeth, a connection located beneath the frame and extending longitudinally of the same from the front of the tooth carrying bar to the front portion of the frame, said connection permitting both an upward and downward 55 and a lateral movement of the tooth carrying bar, and a draft appliance attached directly to the tooth carrying bar at the front thereof and located in rear of the front end of the frame and mounted independently 60 of the latter.

11. An agricultural implement comprising a frame, supporting wheels therefor, a transversely disposed tooth-carrying bar located beneath the frame at a point in advance of 65 the wheels, said bar being composed of a front upwardly extending flange, and a rearwardly extending bottom flange, teeth secured to the rearwardly extending flange of the said bar, means for connecting the tooth- 70 carrying bar with the frame, said means permitting both an upward and downward and a lateral movement of the tooth-carrying bar, and a draft appliance connected with the upwardly extending flange of the tooth 75 carrying bar.

In testimony that I claim the foregoing as my own, I have hereto affixed my signature in the presence of two witnesses.
